UNITED STATES PATENT OFFICE

FRANCOIS XAVIER GAUTHIER, OF MONTREAL, QUEBEC, CANADA

SANDER

Application filed June 17, 1929. Serial No. 371,524.

The invention relates to a sander and the objects of the invention are to produce a sanding machine for use in motor cars, motor trucks, and motor vehicles generally especially for the purpose of facilitating the travel of motor vehicles on ice roads and hills, thereby to a great extent replacing chains commonly used for this purpose, and in an ordinary gravel road the vehicle is very much better without chains, and it is only in slippery places and hills that the aid to the traction is needed and in this connection it may be said that this sanding is also very useful on slippery clay which is frequently a cause of trouble; to minimize the expense in the maintenance of motor vehicles and insure the provision of a means always at hand to grip the road; to construct a machine that may be a permanent part of a vehicle structure or which may be applied as an accessory to used vehicles; and generally to provide a simple, efficient and serviceable device for improved traction conditions.

In the drawings, Figure 1 is a perspective view of the device ready for application to a motor vehicle.

Figure 2 is a perspective detail of the sand nozzle.

Figure 3 is a perspective detail of the sand throttle and electric switch.

Figure 4 is a sectional detail of an electrical terminal and contact.

Figure 5 is a sectional perspective detail showing the assembly of the sand throttle, the electric switch and the discharge from the hopper.

Figure 6 is a sectional detail of the deflecting joint piece.

Figure 7 is a vertical sectional view of the sand hopper and floor, and intermediate parts.

Figure 8 is an elevational view of the device as applied to a motor car.

Like numerals of reference indicate corresponding parts in the various figures.

Referring to the drawings, the sand hopper is indicated by the numeral 15, and this hopper is jacketed forming the warming jacket 16.

The jacket has the inlet 17 and the outlet

18, which are preferably connected to a bypass 19 in the line of piping from the exhaust at the engine.

The hopper is covered except for the filling opening which is closed by the lid 20, and this hopper is secured to the frame of the vehicle through the lugs 21, and tapers down from the top to the outlet passage 22, the deflecting centre piece 23 being supported in the middle of said passage to prevent the clogging of the sand.

The jacket wall is flanged at 24 and to this flange the fan casing 25 is secured by means of a corresponding flange on the neck 26.

The flange 24 on one side is slotted and this slot is closed by the plate 27, this plate supporting the insulation 28, in which the electric terminal post 29 is contained, this contact post being held by the nut 30 forming with the post 29 a passage 31 for the ball contact 32, said ball contact being pressed downwardly by the spring 33, which forms the electric connection between the contact 32 and the post 29.

The ball 32 projects slightly below the nut 30 and is there supported and this nut secures the terminal rigidly to the plate 27.

The sand throttle 34 slides under and closes the passage 22 and slides into the slot in the flange 24 under the ball 32 and is operated by a rod 35 in the dash of the car preferably by a pedal 36 or other form of lever, thus while operating the rod 35 the plate is brought under the ball contact and as this ball contact is electrically connected with the terminal for the electric wiring connection is made to the electric fan 37 operating in the fan casing 25 suitably journalled in the walls thereof.

The neck 26 of the fan casing is formed with the inlet for the falling sand of the motor, and this motor is started previous to the actual opening of the sand outlet, therefore the sand is drawn through and expelled through the outlet passage 38 and into the dividing joint piece 39, where it is guided into the pipes 40 and 41, these pipes being in turn secured to the wide mouthed sand nozzles 42, which are directed on to the wheels of the vehicle.

In the operation of this invention, the hopper is filled or partially filled with dry sand, and this sand is kept very dry by means of the warm jacket, therefore there is not likely to be any clogging through dampness.

5 The operator of the vehicle presses the pedal and this draws the plate under the ball contact 32 whereby the electrical connection is established to the fan motor.

10 The fan is thus suitably driven and draws the dry sand passing it therethrough to the outlet where it is divided and continues in its passage through to the wide mouthed nozzles, which spread it in front of the wheels so as to enable the tires to get a proper grip of the ground.

15 This mechanism may be applied in many different ways to be driven as a superior machine for sanding sidewalks and such places, but the main use of it is on a motor car, in order that it will prove certainly in many instances a good substitute for chains.

20 What I claim is:—

25 In a sander, a hopper having an outlet passage, a closure spring-held in said outlet passage, a deflecting member dividing the sand from said outlet, tubes directing the sand from said divider to the front of the vehicle wheels, splaying nozzles at the ends of said tubes, a blower motor driven and secured below said closure, a rod operated by a suitable lever and operating said closure and electrical means actuated by said closure for starting said motor immediately preceding the running of the sand.

30 Signed at Montreal, Canada, this 30th day of May, 1929.

FRANCOIS XAVIER GAUTHIER.
